MEANS FOR DISTRIBUTING LIQUID
REFRIGERANTS

George M. Kleucker, St. Louis, Mo., assignor, by
mesne assignments, to William P. Gruner, St.
Louis, Mo.

Application March 24, 1939, Serial No. 263,865

6 Claims. (Cl. 62—126)

This invention relates to a certain new and useful means for the distribution of liquid refrigerant.

My invention has for a primary object the provision of a method for the distribution of liquid refrigerant which is efficient and economical, which prevents inefficient heat transfer due to the formation of gas films and gas bubbles upon the heat exchange surfaces, which achieves an intimate contact between the liquid refrigerant film and the surface of the heat exchange means, and which utilizes the mass and movement of the film of liquid refrigerant to shear off or remove intervening films of gas bubbles, oil, and dirt from the heat exchange surface.

My invention has for a further object the provision of means for copiously flowing liquid refrigerant over a heat exchange surface in sufficient mass and with sufficient velocity to prevent the formation of any interfering films of gas bubbles, oil, or dirt and to shear off from said heat exchange surfaces any interfering films of gas bubbles, oil, or dirt which may tend to form thereon.

My invention has for an additional object the provision of means for distributing liquid refrigerant upon heat exchange surfaces which is simple in construction and economical in cost, which may be readily installed in any type of refrigeration system, which may be conveniently adapted to any type of heat exchange apparatus, and which is highly efficient in the performance of its stated functions.

And with the above and other objects in view, my invention resides in the novel features of form, construction, arrangement and combination of parts presently described and pointed out in the claims.

In the accompanying drawings (2 sheets):

Figure 1 is a perspective view, partly broken away and in section, of a heat exchanger equipped with liquid refrigerant distribution means embodying my present invention;

Figure 2 is an enlarged perspective view of the liquid refrigerant distribution means of my invention;

Figure 3 is a transverse sectional view of the heat exchanger and liquid refrigerant distribution means, taken approximately along the line 3—3, Figure 1;

Figure 4 is an enlarged fragmentary vertical sectional view of the heat exchanger and refrigerant distribution means, taken approximately along the line 4—4, Figure 3;

Figures 5, 6 and 7 are modified forms of refrigerant distribution means of my invention;

Figure 8 is a transverse sectional view of a heat exchange tube equipped with the modified form of refrigerant distribution shown in Figure 7;

Figure 9 is a fragmentary vertical sectional view of a "shell-and-tube" type heat exchanger equipped with a modified form of refrigerant distributing means of my invention;

Figure 10 is an enlarged perspective view of a further modified form of refrigerant distribution means of my present invention;

Figure 11 is a transverse sectional view, taken approximately along the line 11—11, Figure 9;

Figure 12 is a fragmentary vertical sectional view, taken approximately along the line 12—12, Figure 11;

Figure 13 is a transverse sectional view of a heat exchange pipe equipped with a further modified form of refrigerant distribution means of my present invention;

Figure 14 is a fragmentary vertical sectional view, taken approximately along the line 14—14, Figure 13;

Figure 15 is a fragmentary perspective view of a further modified form of refrigerant distribution means of my present invention;

Figure 16 is a fragmentary perspective view of a further modified form of refrigerant distribution means of my present invention;

Figure 17 is a fragmentary transverse sectional view of a plurality of heat exchange tubes of the "shell-and-tube" type illustrating the application thereto of refrigerant distribution means of my present invention;

Figure 18 is a fragmentary perspective view of a further modified form of refrigerant distribution means of my present invention; and

Figure 19 is a fragmentary vertical sectional view, taken approximately along the line 19—19, Figure 18.

Broadly speaking, my present invention for the distribution of liquid refrigerant consists in copiously flowing a sheet of liquid refrigerant over a heat exchange surface to form a substantially continuous and uninterrupted film thereon, preventing by scrubbing action the formation of any interfering films of gas bubbles, dirt, or oil.

As is well known, whenever liquid refrigerant is introduced upon a heat exchange surface under certain given conditions of back pressure, a certain proportion of the liquid refrigerant will be evaporated, absorbing from the heat exchange surface the requisite number of heat units re-

quired for such evaporation. Accordingly, I supply a sufficient mass of liquid refrigerant which is substantially greater than the amount of liquid refrigerant which can be evaporated under any given conditions of back pressure by the available number of heat units which may be absorbed from the heat exchange surface. Thus, a substantial excess of liquid refrigerant will flow downwardly over the heat exchange surface and be collected at the bottom thereof. This collected excess of liquid refrigerant is then recirculated to a header at the top of the heat exchange surface, whence it flows downwardly again. In order to compensate for the amount of liquid refrigerant which has been evaporated as a result of heat absorption, I continuously supply fresh liquid refrigerant from the high pressure side of any conventional type of refrigerating system to its low pressure side and the evaporation space in the heat exchanger for the establishment of the desired or selected back pressure.

Accordingly, I may provide a heat exchanger A having upper and lower horizontal headers 1, 2, preferably of elongated hemicylindrical type and connected by a plurality of spaced parallel heat exchange tubes 3 welded or otherwise securely mounted at their ends in, and extending between, the headers 1, 2, as best seen in Figure 1. The header 2 is further provided with a recirculation conduit 4 connected at its outer end to a recirculation pump 5, which, in turn, is connected at its discharge end to a recirculation conduit 6 discharging into the upper header 1.

Also mounted in the lower header 2, is a suction line 7 connected through any conventional type of back pressure control means (not shown) to the low pressure side of any conventional type of compressor (not shown). Similarly mounted in the lower header 2, is a refrigerant supply line 8 connected through any conventional type of control means to the high pressure side of the compressor (not shown), all as best seen in Figure 1.

Welded or otherwise securely mounted in the upper end of each of the heat exchange tubes 3, is a closure plug 9 centrally provided with a refrigerant distributor B, which includes a vertical orifice forming pipe 10 opening at its upper end into the header 1 and provided at its lower orifice end with three radially outwardly extending V-shaped fins or vanes 11, which project downwardly below the discharge mouth of the pipe 10 and are, in turn, provided with a somewhat triangularly shaped horizontally disposed distributor plate 12 arcuately cut away along its margin between the fins 11 in the provision of spreader lips 13, all as best seen in Figure 2 and for purposes presently more fully appearing.

The liquid refrigerant flows downwardly through the pipe 10 and, striking against the upper face of the distribution plate 12, is spread radially outwardly in all directions, as shown in Figure 4, thereby forming a substantially continuous annular sheet around the inner surface of the particular heat exchange pipe 3 and falling downwardly in an uninterrupted cylindrical film having substantial mass and velocity. The liquid refrigerant furthermore swirls around the outer margins of the radial fins 11 in completing the encirclement of the inner face of the heat exchange tubes 3, leaving small free spaces 14, so that any gas which tends to accumulate in the top of the heat exchange pipe 3 may be drawn out under suction without bubbling through the

refrigerant film and breaking or otherwise interfering with it.

I may also provide a modified form of refrigerant distributor C, which includes a pipe 14 having three radially outwardly and downwardly extending arms 15 slightly cupped or concaved at their outer end, as at 16, and integrally formed with a substantially triangular distribution plate 17 having somewhat arcuately inwardly curved marginal lips 18. When positioned in a heat exchange tube 19, the distributor pipe 14 and the associated distributor plate 17 will function substantially in the same manner as the previously described distributor B, producing a ring of liquid refrigerant upon the inner face of the heat exchange tube 19. By reason of the shape of the radial arms 15, small gas evacuating free spaces will be formed, all as best seen in Figure 5.

I may also provide a further modified form of refrigerant distributor D, which includes a pipe 20 provided at its lower or discharge end with three radially outwardly and downwardly extending arms 21 disposed respectively in radial planes and being, in turn, provided at their lower extremities with a somewhat triangularly shaped distributor plate 22 having arcuately inwardly curved discharge lips 23 and downwardly bent triangular projections 24 for breaking the surface tension of the liquid refrigerant film across the under face of the plate 22 in the region of the narrow end portions 25 thereof. When positioned centrally in a heat exchange tube, the distributor D will produce a highly satisfactory uniform cylindrical film or sheet upon the inner face of the heat exchange pipe, all as best seen in Figure 6.

I may also provide a modified form of refrigerant distributor E, which includes a refrigerant supply pipe 20' internally provided with an axially downwardly projecting support member 26 preferably of equilateral Y-shaped transverse cross-section. Welded or otherwise rigidly mounted upon the lower extremity of the support member 26 in concentric alignment with, and extending preferably at right angles to the longitudinal axis of, the tube 20' is a circular distributor disk 26'. When positioned centrally in a heat exchange tube 19, the distributor E will produce a highly satisfactory uniform cylindrical film upon the inner face thereof, as best seen in Figure 8.

My present invention may also be applied with equal facility to shell and tube type coolers in which the substance to be cooled is passed through the interior, and the refrigerant is applied upon the exterior surface, of the heat exchange pipe. For purposes of illustration, I have diagrammatically shown in Figure 9 a shell and tube type cooler A', which includes an upper housing or shell 27 horizontally divided by two spaced parallel tube sheets 28, 29, into an upper header 30 and an intermediate header 31. Extending vertically through the tube sheet 29 and supported in the tube sheet 28 for communication with the header 30, is a plurality of heat exchange pipes 32.

Extending through the wall of the shell 27 and opening into the header 30, is a supply pipe 33 for introducing into the header 30 the substance to be cooled, and similarly mounted in the wall of the shell 27 and opening into the header 31, is a liquid refrigerant supply line 34.

Mounted in the tube sheet 29 in diametrically opposed positions around each of the heat exchange pipes 32, is a pair of refrigerant distrib-

uting jets F including a vertical pipe 35 provided at its lower or discharge end with a horizontally disposed shovel-shaped distributor plate 36 having upwardly presented jet-confining side flanges 37 and a forwardly presented arcuate lip 38 preferably curved to conform to the opposed arcuate segment of the heat exchange pipe 32, all as best seen in Figures 10 and 11.

The liquid refrigerant flows downwardly through the pipe 35 and is directed around the pipe 32 in a uniformly distributed sheet, meeting with the similarly formed refrigerant sheet from the opposite or companion distributing jet F so as to encase the pipe in an uninterrupted downwardly moving cylindrical film.

I may also provide a distributor member G, which includes preferably a plurality of vertical pipes 39 welded or otherwise rigidly mounted at their lower ends in an annular distributing ring 40 of substantially the shape shown in Figure 14.

I have found that I may also apply liquid refrigerant in substantially the same manner to the external surfaces of heat exchange tubes in "shell-and-tube" type coolers by locating a plurality of distributors B in intermediate relationship to the heat exchange pipes b, as illustrated in Figure 17. It will, of course, be apparent in this connection that I may employ either the distributors C or D in the same manner with entirely satisfactory results.

I have also found that my present invention may be applied to flat heat exchange surfaces, in which case I may employ a distributor member F', which is substantially similar in form and construction to the distributor F, except that the forward or discharge lip 38' thereof is of straight line formation to conform to the adjacent surface of the heat exchange plate 41, upon which the liquid refrigerant film or sheet is to be provided. In case the plate 41 is of substantial width, it may be desirable to provide a plurality of distributors F' to insure complete coverage thereof.

Frequently in refrigeration practice, it becomes desirable to employ a pair of relatively closely spaced heat exchange plates 42, 43, in which case I may provide a further modified form of refrigerant distributor H, which includes a vertical pipe 44 provided at its lower or discharge end with an X-shaped discharge plate 45 having upwardly projecting jet-confining flanges 46, 47, along its transverse margins, all as best seen in Figure 16.

In some types of installations, it becomes desirable to employ a substantially wide refrigeration or heat exchange plate 48, in which case I may provide a refrigerant distributor G', which includes a vertical supply pipe 49 provided at its lower discharge end with a preferably horizontal discharge pipe 50 having a plurality of axially extending discharge jets 51 and a tangential plate 52 mounted exteriorly on the pipe 50 and projecting downwardly therefrom in the provision of a jet-distributing flange 53, all as best seen in Figure 19.

It should be understood that changes and modifications in the form, construction, arrangement, and combination of the several parts of the structure may be made and substituted for those herein shown and described without departing from the nature and principle of my invention.

Having thus described my invention, what I claim and desire to secure by Letters Patent is:

1. Liquid refrigerant distributing means com-

prising a refrigerant-containing header, a heat exchanger tube sealed at its upper end in and extending through the header, a plug in the upper end of the heat exchanger tube, a tube mounted in and extending through the plug, said tube having a discharge orifice, a flat circular plate spaced from and extending transversely across said orifice for deflecting the flow of liquid refrigerant therefrom, and a plurality of annularly spaced radial baffles mounted in and projecting axially from the tube for supporting the plate in said spaced relationship.

2. In combination with a heat exchanger tube having a plugged upper end and fixed at such upper end in a refrigerant-containing header, liquid refrigerant distributing means comprising a tube of substantially smaller diametral size than the heat exchanger tube disposed in and extending through the plugged end of the heat exchanger tube for communication at its upper end with the interior of the header and projecting downwardly below the plugged end of the heat exchanger tube, a support member including a plurality of symmetrically arranged radial web members marginally secured to the tube adjacent its lower end and projecting axially downwardly therefrom, and a distributor plate secured upon its upper face to the webs.

3. A heat exchanger tube having a plugged upper end and fixed at such upper end in a refrigerant-containing header, liquid refrigerant distributing means comprising a tube of substantially smaller diametral size than the heat exchanger tube disposed in and extending through the plugged end of the heat exchanger tube for communication at its upper end with the interior of the header and projecting downwardly below the plugged end of the heat exchanger tube, a support member including a plurality of symmetrically arranged radial web members secured at their outer margins to the inner surface of the tube adjacent its lower end and projecting axially downwardly therefrom, and a distributor plate secured upon its upper face to the webs.

4. In combination with a heat exchanger tube having a plugged upper end and fixed at such upper end in a refrigerant-containing header, liquid refrigerant distributing means comprising a tube of substantially smaller diametral size than the heat exchanger tube disposed in and extending through the plugged end of the heat exchanger tube for communication at its upper end with the interior of the header and projecting downwardly below the plugged end of the heat exchanger tube, a support member including a plurality of symmetrically arranged radial web members marginally secured to the tube adjacent its lower end and projecting axially downwardly therefrom, and a distributor plate secured upon its upper face to the web members and extending outwardly therefrom into substantial proximity along its peripheral margin with the inner face of the heat exchanger tube for directing a smooth flowing sheet of liquid refrigerant upon the surface of the heat exchanger tube with a minimum of turbulence and without any substantial spray formation.

5. A heat exchanger tube having a plugged upper end and fixed at such upper end in a refrigerant-containing header, liquid refrigerant distributing means comprising a tube of substantially smaller diametral size than the heat exchanger tube disposed in and extending through the plugged end of the heat exchanger tube for

communication at its upper end with the interior of the header and projecting downwardly below the plugged end of the heat exchanger tube, a support member of equilateral Y-shaped transverse cross-section secured in the lower end of the tube and projecting axially downwardly therefrom, and a distributor plate secured upon its upper face to the lower extremity of the support member.

6. Liquid refrigerant distributing means comprising a refrigerant-containing header, a heat exchanger tube having a plugged upper end and fixed at such upper end in said header, a tube of substantially smaller diametral size than the heat exchanger tube disposed in and extending 10 through the plugged end of the heat exchanger

15 tube for communication at its upper end with the interior of the header and projecting downwardly below the plugged end of the heat exchanger tube, a support member of equilateral

5 Y-shaped transverse cross-section, said support member extending for a substantial portion of its length upwardly into the tube, being secured therein and projecting axially downwardly therefrom for axially splitting the downwardly flowing column of liquid within the tube into three outwardly deflectable smoothly flowing columns of liquid, and a distributor plate secured upon its upper face to the lower extremity of the support member.

GEORGE M. KLEUCKER.
